UNITED STATES PATENT OFFICE.

HENRY DAVENPORT, OF PHILADELPHIA, PENNSYLVANIA.

DESIGN FOR GIMP.

SPECIFICATION forming part of Design No. 13,901, dated May 15, 1883.

Application filed April 7, 1883. Term of patent 3½ years.

To all whom it may concern:

Be it known that I, HENRY DAVENPORT, a resident of Philadelphia, Pennsylvania, and a citizen of the United States, have invented a Design for Gimp, of which the following is a specification.

My design for gimp is shown in the accompanying drawing, and comprises alternating figures *a* and *b*, separated from each other by cross-bars *d*. Each figure *a* is of a substantially oval or diamond shape, and each figure *b* represents a series of bars crossing each other at different angles.

The bars *d* may be omitted without changing the essential character or appearance of the design.

Irrespective of the colors employed, I claim—

1. The design for a gimp, said design comprising the alternating figures *a* and *b*, as shown and described.
2. The design for a gimp, said design comprising the alternating figures *a* and *b* and cross-bars *d*, as shown and described.

In testimony whereof I have signed my name to this specification in the presence of two subscribing witnesses.

HENRY DAVENPORT.
